TOY BLOW LAUNCHER

Allen Cole, 1201 Raydale Road,
Hyattsville, Md. 20783

Filed Sept. 1, 1966, Ser. No. 3,685

Term of patent 3½ years

(Cl. D34—15)

FIG. 1 is an end elevational view of the toy blow launcher showing my new design;

FIG. 2 is a rear elevational view of the toy blow launcher;

FIG. 3 is a top plan view of the toy blow launcher; and

FIG. 4 is a side elevational view thereof.

I claim:

The ornamental design for a toy blow launcher, as shown.
